UNITED STATES PATENT OFFICE.

FRANK J. BAST, OF BROOKLYN, NEW YORK, ASSIGNOR TO CHARLES J. TAGLIABUE
MFG. CO., OF BROOKLYN, NEW YORK, A CORPORATION OF NEW YORK.

FOUNTAIN PEN FOR RECORDING INSTRUMENTS.

Application filed August 7, 1923. Serial No. 656,151.

To all whom it may concern:

Be it known that I, FRANK J. BAST, a citizen of the United States, and resident of the borough of Brooklyn, county of Kings, city and State of New York, have invented certain new and useful Improvements in Fountain Pens for Recording Instruments, of which the following is a specification.

My invention relates to fountain pens for recording instruments in which the pen is automatically controlled and comprises the instrumentality whereby a record is automatically produced upon a chart operatively combined with the recording instrument which may comprise a recording thermometer or the like. Up to the present time fountain pens of this character have included ink channels which of necessity must be of very minute cross-sectional dimensions in order to properly control the flow of ink and which accordingly become very easily clogged up or otherwise disarranged. The particular object of my invention is to simplify the construction of such fountain pens and to do away with the necessity for ink channels of the type referred to and to substitute therefor an arrangement which is efficient in operation and which may readily be maintained in an operative condition of maximum efficiency. Other more specific objects will appear from the description hereinafter.

In the accompanying drawings, Fig. 1 is a sectional view of the fountain pen on an enlarged scale taken on the line 1—1 of Fig. 2, and Fig. 2 is a plan view thereof.

In practice the fountain pen is located at the free end of a pen arm in the customary manner which is operated and controlled by the mechanism forming part of the instrument and whereby the predetermined conditions to be recorded are reflected in the actuation of the pen arm and the fountain pen. The latter, as shown in the drawing, comprises a receptacle or well 5, having one end open and provided with a member 6 extending outwardly therefrom in a radial direction adjacent to the open end of said well. The member 6 is provided with a writing point 7 and in cross-section is of converging form to provide an ink channel 8 which, as shown in Fig. 1 is completely open and, if desired, may be provided with inwardly extending flanges 9 which project toward each other as shown in Fig. 2. The chan-

nel 8 is in communication with the interior of the receptacle or well 5 as illustrated in the drawings. In order to control the flow of the ink to the point 7 a capillary forming wire 10 is provided; the latter comprises a U-shaped section consisting of legs 11 and 12, the former terminating in an eyelet 13 and the latter being continued in the form of a transversely extending member 14. The capillary forming wire is so dimensioned and constructed that the U-shaped section thereof, in practice, extends into the well 5 with the leg 11 in engagement with the inner surface thereof and the eyelet 13 resting upon the upper edge of said well. The leg 12 of the capillary forming wire is spaced to a slight degree from the inner surface of the well 5 at a point diametrically opposite to the leg 11 and forms a capillary channel 15 while the member 14 at its free end 16 rests upon the bottom of the channel 8 and rises from this point to a slight degree toward the leg 12 to form a continuing capillary channel in the channel 8 of the pen 6.

With this arrangement the ink, by capillary action, flows along the capillary channels 15 and 8 to the point 7 of the pen and passes therefrom to the chart in the form of a visible record and in accordance with the movements of the fountain pen as induced by the pen arm and the recording mechanism. The flow of ink is adequately and efficiently controlled by the capillary forming wire 10 in the manner described and passes from joint 7 in exactly the amount required to produce the recording line as the pen arm and pen are automatically actuated. If, for any reason, such as clogging or other disarrangement, it becomes necessary to clean or repair the fountain pen, the capillary forming wire 10, may be removed therefrom by simply exerting a lifting action upon the eyelet 13. When this has been done all parts of the fountain pen are readily accessible and easily cleaned.

The device is extremely simple and does away with the necessity for ink channels in the form of bores of relatively minute dimensions and difficult to maintain in a serviceable condition. The expense incident to the production of such minute ink channels, which is relatively large, is also obviated with the present construction.

The improved fountain pen is adapted

for use in connection with any type of recording mechanism requiring such a pen and may easily and readily replace existing forms of fountain pens.

5 Various changes in the specific form shown and described may be made within the scope of the claims without departing from the spirit of my invention.

I claim:

- 10 1. A fountain pen for recording instruments comprising an inkwell, a pen projecting therefrom and provided with an exposed ink channel, and a wire extending into said inkwell and lengthwise of said ink
- 15 channel and forming a capillary channel in the ink well and lengthwise of the pen for controlling the flow of ink along said ink channel.

2. A fountain pen for recording instruments comprising an inkwell, a pen projecting outwardly therefrom in a radial direction and having an exposed ink channel, a capillary forming wire having a U-shaped section extending into said well with one leg in engagement with the inner surface thereof and the other leg spaced from said inner surface to form a capillary channel and a transverse member extending lengthwise of said ink channel at an inclination relatively thereto to form a continuing capillary channel whereby the flow of ink to the pen point is controlled.

In testimony whereof I have hereunto set my hand.

FRANK J. BAST.
